**MOVABLE AND FOLDING BARRIER COMPONENT
FORMING A BARBED WIRE ENTANGLEMENT
FOR MILITARY AND OTHER PURPOSES**

Jacques Léon Alexandre See, Suresnes, France

Application July 11, 1955, Serial No. 521,338

Claims priority, application France August 20, 1954

10 Claims. (Cl. 256—2)

Up till now, barrier components, forming barbed wire entanglements, and in particular, "chevaux de frise," have been difficult to transport, owing to their very considerable volume.

This invention obviates these disadvantages, by producing movable and folding barrier components forming barbed wire entanglements that can be transported flat; the framework components of these entanglements can be superimposed.

According to the invention, the movable and folding component forming a barbed wire entanglement for military and other purposes is characterised by the fact that it is made up of a certain number of cross-shaped components, lined up one behind the other and forming barrier components; these components comprise a hoop in the middle and are connected to each other, on the one hand, by barbed wires extending longitudinally and transversally through the entanglement, and on the other hand, diagonally, the latter wires connect two non-adjacent components of the framework.

Various other characteristics of the invention will moreover be revealed by the detailed description that follows.

One form of embodiment of the invention is shown, by way of example, in the attached drawing.

Figure 1 is a perspective view of the movable and folding barrier component.

Figure 2 is a corresponding longitudinal elevation on a smaller scale.

Figure 3 is a corresponding plan view on a smaller scale.

Figure 4 is an end elevation.

Figure 5 is a perspective view of a part of a movable barrier component showing an alternative scheme.

Figure 6 is a perspective view of part of another alternative.

Figure 7 is a perspective view of a barrier component holder.

Figure 8 is a partial elevation showing another form of fitting.

The barrier component consists of a framework 1 of sectional iron made up of components 2. The latter comprise a hoop 3 on to which two V-shaped holders 4, 5 rounded at the base, are welded, these two holders being diametrically opposed with regard to the hoop 3.

The ends 4a, 4b, and 5a, 5b of the holders 4, 5 are cut so as to make points. Barbed wires 6 join the four arms of the holders 4, 5 near to their end.

For handy reference purposes, the various components shown in Figure 1 are marked A, B, C, D, E, F. Four barbed wires 7 connect the components A, B, C, D, E, F to the four ends of the arms of the holders 4, 5 in the longitudinal direction of the barrier.

Four barbed wires 8, 9, 10 and 11 connect the ends 4a, 5a, 4b and 5b to the component A at the ends 5b, 4b, 5a and 4a of the component C. Likewise for the component B with the component D, and so on. The barbed wires 8, 9, 10 and 11 pass through the hoop 3 of the

2

component placed between the two connected components.

Furthermore, four wires 12, 13, 14 and 15 fixed to the four inside angles of the holders 4, 5 of the component A connect the latter to the ends 4a, 5a, 4b and 5b of the component B.

The ends 4a, 5a, 4b and 5b of the component E are connected by wires to the four inside angles of the holders 4, 5 of the component F.

10 The wires 6, 7, 8, 9, 10, 11 and 12, 13, 14, 15 are barbed wires and owing to their arrangement it is impossible to pass through the barrier component.

To fold the entanglement one turns the assembly of the components A, B, C, D, E in the direction of the arrow F₁ (Fig. 1) while keeping the component F motionless; then, after a rotation in proportion to the length of the barrier, the components A, B, C, D, E, F are brought together. It is thus easy to transport the barrier flat.

15 The various components A, B, C, D can also be alternatively turned for 90° in either direction.

The lower ends of the arms of the holders 4, 5 are fixed in the ground and thus afford sound frontal and side stability to the assembly.

20 Several components can be grouped to form barbed wire entanglements surrounding the space to be protected.

In Figure 5, the frames 1 each comprise a hoop 3 with arched parts 15 arranged at 90° to each other on the hoop 3.

25 The arms or holders 4 forming legs are sharpened at their free ends to enable, on the one hand, the barrier component to be fixed in the ground, and on the other hand, to afford close-up protection to the barrier component. A second hoop 16 is fixed on the four legs to make each frame rigid.

30 Barbed wires 7 connect the free ends of the legs 4 of the frames A, B . . . in a longitudinal direction, whereas other barbed wires 8 placed diagonally, connect two non-adjacent frames, so as to prevent the barrier component from being easily penetrated. The wires 8 arranged diagonally pass through spaces provided between the inside hoop 3 and the outside hoop 16 of the frame placed between the two connected frames. Owing to 35 this fact, the space restricted by the inside hoops 3 of the frames through the length of the barrier is free and the barrier component can thus be slipped on to a cylindrical holder 19 (Figure 7) which is provided with a cam 20 along one of its generatives which is movable and makes an abutment. Moreover, this cam enables the barrier component to be unwound, frame by frame.

35 Alternatively, by placing the frame 1 on the holder 19 and making a rotation of 90° for each frame in one direction, or alternatively, in both directions, the barbed wires connecting the various frames to each other are folded without the risk of tangling, and barrier components of appreciable length are obtained, which, when folded take up very little space, which facilitates their transport.

40 In Figure 6, each frame 1 comprises an inside hoop 3 with arches 15 arranged at 90° to each other. The inside hoop 3 of each frame is supported by four curved iron parts 21 fixed around the inside hoop 3 at 90° to each other, so as to form four cross-shaped arms, these arms being identical. The frames 1 thus formed are connected as described above by barbed wires, the wires placed diagonally passing through the spaces restricted by the ends of the curved iron parts 21 so that the central inside space of the barrier component is free to enable the barrier component to be wound on a holder similar to that shown in Figure 7. The ends of the curved iron parts 21 are cut in a point to enable the barrier com-

ponent to be inserted in the ground and at the same time, to effect a close-up protection for the barrier.

In Figure 8, the arms 4 are fixed to the hoops 3 and 16 by making a loop round each hoop, so as to obviate welding.

The inside hoops 3 may comprise any number of arches 15, likewise the arms 4 can be distributed in any number around the inside hoops.

Various modifications can moreover be applied to the forms of embodiment, given as examples, without going outside the scope of the invention.

I claim:

1. A portable barrier structure for forming a barbed wire entanglement, comprising a plurality of rigid frame components in spaced parallel relation, each of said components including a centrally disposed hoop with arms radiating therefrom, barbed wires connecting the end portions of corresponding arms of said components, and barbed wires connecting the end portions of diametrically opposite arms of non-adjacent components and passing through the hoops of the intermediate components.

2. A portable barrier according to claim 1 wherein the ends of said arms are pointed.

3. A portable barrier according to claim 2 including barbed wires extending between the end portions of the arms of each component.

4. A portable barrier according to claim 1 wherein the length of the wires connecting corresponding arms of adjacent components are of a predetermined length to be stretched taut when said components are relatively rotated and collapsed together in registered relation.

5

6. A portable barrier according to claim 4 wherein

the length of the wires connecting corresponding arms of

adjacent components is equal to the spacing between

adjacent arms of each component whereby said barrier

may be collapsed for transport with said components in

alignment by revolving each component.

7. A portable barrier according to claim 5 wherein

the arms of each component are formed by a pair of

V-shaped members having arcuate bases which are fixed

to the hoop.

8. A portable barrier according to claim 1 wherein

each component comprises a second hoop concentric

with and larger than said central hoop, said second hoop

being connected to said arms.

9. A portable barrier according to claim 1 wherein

said central hoop has arched portions between said arms.

10. A portable barrier according to claim 9 wherein

said component arms comprise two curved elements

joined at their ends and spanning said hoop between said

arched portions.
